RECORDING AND REPRODUCTION OF
ELECTRICAL IMPULSESAbraham Ringel, Merchantville, N. J., assignor to
Radio Corporation of America, a corporation of
Delaware

Application February 1, 1933, Serial No. 654,667

21 Claims. (Cl. 179—100.1)

This invention relates to the recording and reproduction of electrical impulses such as those found within the audio frequency range, and has for its principal object the provision of an improved apparatus and method of operation whereby ground or background noise is eliminated, the volume range in sound recording and broadcasting is increased, and overshooting due to over-modulation of the sound during recording is prevented.

In the reproduction of sound, and particularly of music, two essential factors must be considered, namely, quality and quantity. In music these factors are referred to as "tone color" and "tone volume"; in engineering they are associated with frequency response and amplitude, respectively. The performance of apparatus with regard to the reproduction of a wide frequency range has received a great deal of attention and considerable advance has been made in recording and amplifying equipment. However, musicians have many times commented upon and objected to the compression of volume range which has appeared to be necessary, because of apparatus limitations. The lower limit of volume is governed by the so-called "noise level", while the upper limit is governed by the overload point of the equipment. In recording, this point is reached when one groove is over-cut into the adjacent groove.

At the present time, the permissible volume range in either broadcasting or disc recording is of the order of 25 or 30 decibels (approximately 30 to 1 in amplitude). From the standpoint of the musician, it would be highly desirable to have this range increased to 60 or 70 db., to reproduce, for instance, the music of a symphony orchestra. Such a range cannot be realized without resorting to some means of volume control additional to that inherent in the record or broadcasting system. This invention relates to a method of obtaining an increase in the existing volume range by the use of "volume-controlling" signal, referred to hereafter as the "control-tone". With the equipment described, the volume range in phonograph reproduction can be extended to at least 50 db.

Briefly, the broadening of the reproducible dynamic or volume range is accomplished in the following manner. Suppose that a passage is being recorded, whose minimum amplitude is lower than the ground noise of the system. Heretofore, the gain of the recording amplifier was raised at this point to raise the level of the music to a value above that of the noise. In accordance with this invention, the recordist increases the gain in the same manner, but he also adds an additional sub-audible tone, having a different frequency such as 20 cycles, to the cutter's input. When the record is later reproduced, the voltage obtained from this additional control tone is used

to reduce the gain of the reproducing amplifier. In this manner, the reproduced signal may be reduced very nearly to the original level, and at the same time the favorable signal to noise ratio, obtained by raising the signal level in recording, is maintained. The limit of maximum reproducible amplitude is, of course, determined by the reproducing equipment and may be made as high as desired so that the reproduced dynamic range may be made almost identical with the original.

As hereinafter explained, these various results are achieved by the utilization of a volume control current which has a frequency outside the frequency range of the desired signals, is recorded simultaneously with the signals on the same record area, and has its level controlled either manually or automatically to maintain the desired signal at a continuously high level or within a comparatively narrow range of levels. Thus in the case of sound recording and reproduction, the control current may, for example, have a sub-audible frequency and may have its level controlled to increase the volume of the audio impulses at low modulation and to decrease the volume of these impulses at high modulation, thus maintaining the signal current within a comparatively narrow range of levels. During reproduction, the control current is separated from the signal current either electrically or electromechanically and is rectified and is utilized to restore the volume of the reproduced sound to its original value. It will be readily understood that such a control current may also be utilized in connection with radio broadcasting to correct inaccuracies due to defective rendition in the studio and the like.

Further objects of the invention are to increase the dynamic range of disc reproduction from approximately 25 db., as at present, to 50 db., to increase the signal to noise ratio in reproduction to a more favorable value by permitting the recording to be done at a high and more or less uniform level, and reducing this level to the original by means of the control tone, and to extend the volume range of sound film reproduction or radio broadcast transmission.

The invention will be better understood from the following description when considered in connection with the accompanying drawings and its scope will be pointed out in the appended claims.

Referring to the drawings:

Fig. 1 is a diagrammatic representation of a recording system involving the invention.

Fig. 2 is a diagrammatic representation of a reproducing system constructed in accordance with the invention.

Fig. 3 is a modified form of recording apparatus arranged for automatic volume control of the recorded sound.

Figs. 4, 5 and 6 are explanatory diagrams il-

60

lustrating different types of record made in accordance with the invention.

Fig. 7 is a side view of an electrical reproducer which is operable electromechanically to separate the control and signal impulses reproduced from a grooved disk or the like.

Fig. 8 is a plan view of the part of the reproducer which functions to reproduce the control impulses recorded on a grooved disk, and

10 Fig. 9 is an explanatory diagram relating to the operation of the composite reproducer of Figs. 7 and 8.

The recording system of Fig. 1 includes a microphone or pick-up device 10 from which electrical impulses are supplied to a recorder 11 through a suitable channel including an amplifier 12, an adjustable volume control potentiometer 13, a high pass filter and a recording amplifier 14. It will be apparent that the channel 12-13-14 20 may include additional elements such as a mixer and other usual elements utilized in a channel of this character, and that the recorder 11 may be constructed to record on a grooved disk, on photographic film or on other suitable recording material.

Control current produced by a generator 15 is injected into the channel 14 through means including a potentiometer 16 which may be mechanically coupled to the potentiometer 13, a coupling tube 17, a transformer 18 and a low pass filter 19.

Under these conditions the signal and control currents are simultaneously recorded on the same recording area or sound track. The levels or 35 volumes of the control and signal currents may be varied simultaneously in the case of integral control of the potentiometers 13 and 16. If the signal currents are of audio frequency, the frequency of the control current may lie within 40 the subaudible range, a frequency of the order of 20 cycles being suitable for this purpose. If the original sound is too loud to be recorded or modulated, its volume is reduced and the volume or amplitude of the control current is decreased 45 correspondingly at the same time. If the original sound is so weak that it might be masked by needle scratch, background or ground noise due to dirty or scratched film or the like, the signal level and the control current level are raised, 50 thus maintaining the recorded signal within a comparatively narrow range of levels, reducing ground noise due to the relatively high level of the signal, preventing overshooting of the recorder, and increasing the volume of signal which 55 may be recorded.

It is desirable that about 90% of the sound track area should be allowed for the sound record and that the remainder utilized to record the control current i. e. a maximum of about 90% 60 of the sound track should be utilized for the loudest sound or the highest percentage modulation. The lowest recording level of the signal should not be less than 25 to 30 per cent of full scale. If the signal level decreases below this range of 65 values, the potentiometers 13 and 16 are operated to raise the levels of the signal and control currents to the proper value.

During silent passages, the gain is increased by the potentiometers 13 and 16 to a point where 70 the control current is recorded at maximum level so that the high amplitude of the control current will reduce the amplification of the system and thereby lower the ground noise levels in the silent passages during reproduction. When the 75 level of the recorded control current is high, the

volume of the reproduced sound is low. When the recorded level of the control current is low, the volume of the reproduced sound is high. Intermediate reproduced sound volumes in the range of 30 to 90 percent of full scale require 5 no change.

As will be readily understood, this invention is designed to take care of ranges above 90% and below 30% in normal recording so that the entire record is compressed in the range of 30 to 10 90 percent of full scale, the required difference in intensities or volumes being the result of the variation in amplification produced by the control current which occupies the remainder of the record and is superimposed on the sound 15 record. In this manner, a voltage ratio of 30 to 1 is readily obtained for sound that would normally record less than 30 percent of full scale and a ratio of 10 to 1 is obtained for sound that would record more than 90 percent or exceed 20 full scale. This invention therefore makes it possible to obtain a voltage range of $30 \times 3 \times 10$, or 900 to 1, i. e., at least 60 decibels range without ground noise as compared with the 30 to 35 range heretofore possible.

25 The reproducing system of Fig. 2 includes a record 20 and a pick-up device 21 from which electrical impulses are supplied to a loud speaker 28 through an amplifier 22, a coupling transformer 23, a pair of push-pull connected variable μ tubes 24-25; a transformer 26 and a power amplifier 27. A resistor 28 is connected in the common lead of the input circuits of the tubes 24-25. Volume control current is supplied to this resistor from the pick-up device 21, the amplifier 22, a filter 29 for separating the control current from the signal current, a rectifier 30 for producing a direct current which varies in accordance with the level of the control current and a filter 31 for smoothing out the rectified 40 impulses.

As hereinafter explained in connection with Figures 7, 8 and 9, the function of separating the signal and control current impulses may, in the case of reproduction from a disk record, be 45 performed by a composite pick-up device instead of the electrical filter 29.

It will be apparent that the rectified control current supplied to the resistor 28 which is connected in the input circuit of the vacuum tubes 50 24-25 will vary the bias on the control grids and thus function to vary the amplification and volume of the reproduced sound, this volume being reduced when the level of the control current is high and being increased when the level 55 of the control current is low. It should be noted that the variable μ tubes 24 and 25 may be of the type commonly having the designation UX-235 or RCA-58. The power amplifier 27 may be omitted if these tubes are designed to 60 have sufficient output current to operate the loud speaker 28.

Although the volume control of the recording system of Fig. 1 is effected by manual manipulation of the potentiometers 13 and 16, automatic 65 means may be provided for producing this result. Thus in the recording system of Fig. 3, electrical impulses are supplied from the pick-up device or microphone 10 to the recorder 11 through a channel including the amplifier 12, a transformer 35, 70 a push-pull amplification stage 36-37 containing variable μ tubes, a transformer 38, a high pass filter 39-40-41, and the power amplifier 14. Volume control current is supplied from the generator 15 to the recorder 11 through a channel 75

including a transformer 42, a push-pull amplification stage 43-44 using variable μ tubes, a transformer 45, a low pass filter 46-47-48 and the power amplifier 14.

- 5 Current for automatically controlling the levels or volumes of the signal and control currents as previously explained is derived from a secondary winding 50 of the transformer 35. It will be observed that current from this winding is supplied 10 through an amplifier 51, a transformer 52, an amplifier 53, a transformer 54, a rectifier 55 and a filter 57-58-59 to a resistor 60 connected in the input or control circuit of the amplifier 36-37 of the signal channel, and to a resistor 61 connected 15 in the control circuit of the amplifier 43-44 of the control channel.

It is apparent that proper adjustment of the input potentiometers 60 and 61 will result in automatic variation of the control and signal 20 current levels in the manner explained in connection with the system of Fig. 1. Thus when the signal current level is low, the voltage drops across the resistors 60 and 61 will be comparatively low and the signal and control current 25 levels will increase. When the signal current level is high, however, the voltage drops of the resistors 60 and 61 will be comparatively high and the signal and control current levels will decrease. When no signal current exists, the voltage 30 drop of the resistor 61 is very low and the level of the control current has its maximum value.

If the recorder is of the photographic type, the sound record appears somewhat as indicated in 35 Fig. 4, the control current being indicated as a sine curve 62 on which are superimposed the signal waves 63. In the short record illustrated it is of course impossible to show variations in level. In the case of the grooved record of Fig. 5, the audio waves are likewise superimposed on a 40 groove of sinusoidal form. In Fig. 6, the signal current is roughly indicated by the curve A, the control current by the curve B, and the resultant current by the curve C.

45 The electrical reproducer illustrated by Figs. 7 and 8 includes an electrical reproducer 70 provided with a support or tone arm 71 pivoted at 72. This reproducer 70 reproduces signal current from the record 73 in the usual manner and its 50 operation will be readily understood without further explanation.

Mounted upon the tone arm 71 by means including a bolt 73 and a spacer 74 is a reproducer 75 which functions to reproduce the control current impulse recorded on the record 73. This 55 control current reproducer includes a magnet 76 which is provided with an armature 77 mounted on a resilient support 78 and having an adjustable weight or inertia means 79 for tuning the reproducer to the control frequency. Mounted on the armature 77 near the pole pieces of the magnet 76 is a pick-up coil 80 wherein the control current is generated.

60 The manner in which the electrical pick-up device 75 is tuned by adjustment of the weight 79 along the armature 77 will be apparent upon examination of Fig. 9 wherein

m_1 =moment of inertia of the needle about the pivot,

70 C_1 =compliance of the needle point,

m_2 =moment of inertia of the pick-up armature about the pivot,

C_2 =compliance of the rubber damping of the armature,

75 R_1 =resistance of the rubber,

m_3 =moment of inertia of the tone arm 71 about its horizontal axis,

C_3 =compliance of the tone arm 71,

m_4 =moment of inertia of the tone arm about its vertical axis,

5 m_5 =moment of inertia of the armature 77, and

C_4 =compliance of the suspension of the armature 77.

By suitable adjustment of the weight 79 the 10 factor m_5 may evidently be made to have any value required to cause the reproducer 75 to respond to the control current frequency utilized. As will be readily understood by those skilled in the art, this type of filtering is of particular advantage when a control current of relatively low frequency is utilized. How the control current thus separated from the signal is utilized to control the volume of the reproduced sound will be evident in view of what has been said with respect to Fig. 2.

From the foregoing explanation, it will be evident that the invention is not limited to the particular embodiment described but that various changes may be made without surrendering any 25 of the advantages which it has made possible.

I claim:

1. The method of sound recording and reproducing which includes superimposing on the audio impulses a control current of inaudible frequency, raising the level of said control current when the volume of said impulses is relatively low and lowering said level when said volume is relatively high, reproducing said current and impulses, and controlling the volume of said reproduced impulses in accordance with said reproduced current.

2. The method of sound recording and reproducing which includes superimposing on the audio impulses a control current of inaudible frequency, raising the level of said control current when the volume of said impulses falls below thirty per cent of its full scale value and lowering said level when said volume exceeds ninety per cent of its full scale value, reproducing said 45 current and impulses, and controlling the volume of said reproduced impulses by means of said reproduced current.

3. The method of sound recording and reproduction which includes superimposing on the audio impulses a control current of inaudible frequency, raising the level of said control current when the range of said volume is relatively low and lowering said level when said range is relatively high, reproducing said impulses and 55 current, and controlling the volume of said reproduced impulses by means of said reproduced current.

4. The method of sound recording and reproducing which includes superimposing on the audio impulses to be recorded a control current of inaudible frequency, raising the levels of said impulses and current during the lower volume ranges of said sound and lowering said levels during the higher volume ranges of said sound, 65 reproducing said impulses and current, and restoring the level of said reproduced impulses to its original value by means of said reproduced current.

5. The method of sound recording and reproducing which includes superimposing on the audio impulses to be recorded a control current of inaudible frequency, producing a composite record of said impulses and current, reproducing said impulses and current from said record, 75

- and controlling the volume of said reproduced impulses by means of said reproduced current.
6. The method which includes producing audio impulses, superimposing a current of inaudible frequency on said impulses, reproducing said impulses and current, and controlling the volume of said reproduced impulses by means of said reproduced current.
7. The combination of means for subjecting a light sensitive record to light modulated in accordance with electrical impulses, means for superimposing on said impulses additional impulses of a frequency without the range of said modulating impulses, and means for simultaneously varying the levels of said impulses.
8. The combination of means for subjecting a light sensitive record to light modulated in accordance with electrical impulses, means for superimposing on said impulses additional impulses of a frequency without the range of said modulating impulses, means for simultaneously varying the levels of said impulses, means for reproducing said impulses, and means for causing the volume of said reproduced modulated impulses to be controlled in accordance with the level of said reproduced additional impulses.
9. The combination of means for subjecting a record area to impulses within one range of frequencies and to an impulse of a frequency without said range, means for reproducing said impulses from said record, and means for causing the volume of the impulses reproduced within said range to be controlled by the impulse reproduced without said range.
10. The combination of means for producing audio impulses, means for producing an inaudible impulse, and means responsive to said audio impulses for controlling the levels of said audible and inaudible impulses.
11. The combination of means for producing audio impulses, means for producing an inaudible impulse, means responsive to said audio impulses for controlling the levels of said audible and inaudible impulses, and means for causing said audible and inaudible impulses to be recorded in superimposed relation with respect to one another.
12. The combination of means for producing audio impulses, means for producing an inaudible impulse, means responsive to said audio impulses for controlling the levels of said audible and inaudible impulses, means for causing said audible and inaudible impulses to be recorded in superimposed relation with respect to one another, means for reproducing said audio and inaudible impulses, and means for causing the volume of said reproduced audio impulses to be controlled by said reproduced impulse of inaudible frequency.
13. The method of sound recording and reproducing which includes superimposing on the audio impulses a control current of inaudible frequency, lowering the level of said control current when the volume of said impulses is relatively high, reproducing said current and impulses, and controlling the volume of said reproduced impulses in accordance with said reproduced current.
14. The method of sound recording and reproducing which includes superimposing on the audio impulses a control current of inaudible frequency, raising the level of said control current when the volume of said impulses falls below thirty percent of its full scale value, reproducing said current and impulses, and controlling the volume of said reproduced impulses by means of said reproduced current.
15. The method of sound recording and reproduction which includes superimposing on the audio impulses a control current of inaudible frequency, raising the level of said control current when the range of said volume is relatively low, reproducing said impulses and current, and controlling the volume of said reproduced impulses by means of said reproduced current.
16. The method of sound recording and reproducing which includes superimposing on the audio impulses to be recorded a control current of inaudible frequency, raising the levels of said impulses and current during the lower volume ranges of said sound, reproducing said impulses and current, and restoring the level of said reproduced impulses to its original value by means of said reproduced current.
17. The combination of means for subjecting a record area to impulses within one range of frequencies and to an impulse of a frequency without said range, means for reproducing said impulses from said record, means for separating said reproduced impulse from said reproduced impulses, and means for causing the volume of said reproduced impulse to be controlled by said reproduced impulse.
18. The combination of means for subjecting a record area to impulses within one range of frequencies and to an impulse of a frequency without said range, means for reproducing said impulses from said record, electrical means for separating said reproduced impulse from said reproduced impulses, and means for causing the volume of said reproduced impulses to be controlled by said reproduced impulse.
19. The combination of means for subjecting a record area to impulses within one range of frequencies and to an impulse of a frequency without said range, means for reproducing said impulses from said record, mechanical means for separating said reproduced impulse from said reproduced impulses, and means for causing the volume of said reproduced impulses to be controlled by said reproduced impulse.
20. The combination of means for subjecting a record area to impulses within one range of frequencies and to an impulse of a frequency without said range, means for reproducing said impulses from said record, means including a composite reproducer for separating said reproduced impulse from said reproduced impulses, and means for causing the volume of said reproduced impulses to be controlled by said reproduced impulse.
21. Apparatus comprising a pickup device, means operatively associated with the pickup device for reproducing, as sound, vibrations made effective in the pickup device, control means for controlling the intensity of the sound sequence so reproduced, and means operatively associated with the pickup device and sensitive to control vibrations made effective in the pickup device for actuating the control means in response to control vibrations made effective in the pickup device.

ABRAHAM RINGEL.
